UNITED STATES PATENT OFFICE.

GEORGE A. ANDERSON, OF FARGO, NORTH DAKOTA.

MECHANICAL MOVEMENT.

941,003.

Specification of Letters Patent. Patented Nov. 23, 1909.

Application filed January 20, 1909. Serial No. 473,387.

To all whom it may concern:

Be it known that I, GEORGE A. ANDERSON, a citizen of the United States, residing at Fargo, in the county of Cass and State of North Dakota, have invented certain new and useful Improvements in Mechanical Movements; and I do hereby declare the following to be a full, clear, and exact description of the invention, such as will enable others skilled in the art to which it appertains to make and use the same.

My invention has for its object to provide an improved mechanical movement adapted to convert rotary motion into reciprocatory motion and vice versa.

To the above ends, the invention consists of the novel devices and combinations of devices hereinafter described and defined in the claims.

20 In the accompanying drawings which illustrate the invention, like characters indicate like parts throughout the several views.

Referring to the drawings: Figure 1 is a view in side elevation, with some parts sectioned, showing the improved mechanical movement; and Fig. 2 is an edge elevation of the parts shown in Fig. 1.

The numeral 1 indicates a rotary head having three points or tooth like projections 2, located equidistant from its axis and spaced 120 degrees apart. As shown, this head is carried by a rotary shaft 3.

The numeral 4 indicates a plunger or bar which is mounted to reciprocate in a guide 5, and preferably is free for slight movement from left toward the right in respect to Fig. 1. At its upper end, this plunger 4 is provided with a frame or head 6 that is formed with an approximately elliptical

40 opening 7, the major axis of which, extends longitudinally of said plunger 4. At its sides and on the line of its minor axis, this elliptical opening or seat 7 is formed with notches 8. Preferably, the frame 6 is made in two parts, the removable section thereof being rigidly but detachably secured to the main section by screws or bolts 9. The main reason for making the frame 6 in two parts, is to provide for adjustment by filing of the 50 engaging surfaces of the two sections, to compensate for wear of the surface of the elliptical seat or opening 7.

The points 2 of the rotary head 1 are adapted to engage, one after the other, with the notches 8 of the elliptical seat 7, and they are so extended or projected, that when

one point 2 is engaged with two of the notches 8, a second point can pass into and out of the opposite notch 8, and a third point will engage with some portion of the 60 elliptical seat 7. This action is illustrated by dotted and full lines in Fig. 1. Assuming that the head 1 is being positively rotated or driven in the direction of the arrow marked thereon in Fig. 1, it will be 65 seen that the left hand point 2 has just passed out of engagement with the left hand notch 8, and the right hand point 2 is held in engagement with the right hand notch 8, so that it will positively hold the frame 6 70 and its plunger 4, approximately to the position shown by dotted lines in Fig. 1. When the head 1 is rotated slightly farther than shown by dotted lines in Fig. 1, the right hand point will pass out of engagement with the right hand notch 8, and the left hand point 2 will be forced into engagement with the left hand notch 8, and thus, will force the said frame 6 downward until it reaches the position shown by full lines in Fig. 1, in 75 which position the parts again assume the position shown by full lines in Fig. 1, and the said frame is again moved upward. In this way, it is evident, rotation of the head 1 reciprocates the frame 6 and its plunger 4. 80 It is possible by reciprocatory movements of the frame 6, to rotate the head 1 by a reverse action.

It will be observed that the points 2 of the rotary head 1 engage in succession with the 90 notches 8, first on one side and then on the other, so that for each complete rotation of the said head 1, the frame 6 and its plunger 4 will be given three complete reciprocations, or in other words, will be moved three 95 times upward and three times downward.

It will, of course, be understood, that this mechanical movement may be employed generally wherever it may be found desirable, for converting rotary into reciprocating motion.

What I claim is:

1. The combination with a reciprocatory frame having an approximately elliptical seat formed with side notches located on its 105 minor axis, of a rotary head working within said seat, provided with three points located equidistant from its axis and circumferentially spaced 120 degrees apart, the points of which head are arranged to move 110 over the elliptical surface of said seat, and to engage in succession with the said side

notches of said seat, whereby rotation of said head will reciprocate said frame or vice versa.

2. The combination with a reciprocatory frame having an approximately elliptical seat formed with side notches located on its minor axis, of a rotary head working within said seat, provided with three points located equidistant from its axis and circumferentially spaced 120 degrees apart, the points of which head are arranged to move over the elliptical surface of said seat, and to en-

gage in succession with the said side notches of said seat, whereby rotation of said head will reciprocate said frame or vice versa, and which frame is made up of two detachably connected sections, divided on one of the axes of said elliptical seat. 15

In testimony whereof I affix my signature in presence of two witnesses.

GEORGE A. ANDERSON.
